COMBINATION ARTICLE OF FURNITURE

Muriel C. Jones, Victoria, British Columbia,
Canada

Application October 10, 1950, Serial No. 189,395

4 Claims. (Cl. 5—2).

1

This invention relates to furniture, and more particularly to a combination chest, crib and storage case.

An object of this invention is to provide a combination chest, crib and storage case in which the crib and storage case can be readily assembled within the chest and will appear to be a part of the latter.

Another object of this invention is to provide a combination chest, crib and storage case which is particularly adapted to receive a pre-school age child and to store the child's wearing apparel and other effects.

A further object of this invention is to provide a combination chest, crib and storage case which is particularly adapted for movement to various locations with speed and facility.

A still further object of this invention is to provide a combination chest, crib and storage case for use in cramped living quarters, wherein it is desirable to have a single piece of furniture serve several functions to conserve valuable living space.

A still further object of this invention is to provide a combination chest, crib and storage case which is relatively simple in structure and cheap to manufacture.

The above and still further objects and advantages of the invention will become apparent upon consideration of the following detailed description of the invention when taken in conjunction with the accompanying drawings, wherein:

Figure 1 is a perspective view of the combination article of furniture of the present invention, shown with the crib-forming receptacle and the drawer partially extended;

Figure 2 is a perspective view, with parts broken away and shown in section, of the crib-forming receptacle of the combination article of furniture of the present invention, shown with the crib guard rail supported in its extended position;

Figure 3 is a front elevational view of the combination article of furniture shown in Figure 1;

Figure 4 is a sectional view taken along the line 4—4 of Figure 3;

Figure 5 is a sectional view taken along the line 5—5 of Figure 3;

Figure 6 is a transverse sectional view of the crib-forming receptacle shown in Figure 2;

Figure 7 is an enlarged fragmentary sectional view taken along the line 7—7 of Figure 6;

Figure 8 is a perspective view of a modified form of the combination article of furniture of the present invention; and

2

Figure 9 is a perspective view of the open-top storage receptacle forming a part of the combination article of furniture shown in Figure 8.

Referring now more particularly to the drawings, wherein like reference numerals have been used throughout the several views to designate like parts, there is shown the combination article of furniture of the present invention, generally designated by the reference numeral 10, which embodies a chest or cabinet 11 having an open front 12, an open-top receptacle 13 conformably received within the lower portion of the chest 11 and mounted in the latter for extensible and retractile movement with respect to the open front 12 thereof, and an open-top drawer 14 conformably received within the upper portion of the chest 11 and mounted in the latter for extensible and retractile movement with respect to the open front thereof.

10 The chest or cabinet 11 embodies a pair of up-standing side walls 15 and 16 arranged in spaced, parallel relation with respect to each other and secured together by means of the top wall 17 and the back wall 18. The side walls 15 and 16, the top wall 17 and the back wall 18 cooperate to define a rectangular chest having the open front.

15 20 The chest or cabinet 11 embodies a pair of up-standing side walls 15 and 16 arranged in spaced, parallel relation with respect to each other and secured together by means of the top wall 17 and the back wall 18. The side walls 15 and 16, the top wall 17 and the back wall 18 cooperate to define a rectangular chest having the open front.

25 20 The chest or cabinet 11 embodies a pair of up-standing side walls 15 and 16 arranged in spaced, parallel relation with respect to each other and secured together by means of the top wall 17 and the back wall 18. The side walls 15 and 16, the top wall 17 and the back wall 18 cooperate to define a rectangular chest having the open front.

The open-top receptacle 13 embodies a pair of spaced, side walls 19 and 20 interconnected by the front and rear panels or walls 21 and 22. Fixedly secured within the assembly of the side walls 19 and 20 and the front and rear walls 21 and 22 is a bottom wall 23 which is spaced above a floor surface 24 upon which the article of furniture is to be supported.

35 Resting upon the bottom wall 23 of the open-top receptacle 13 is a mattress 25 which is removably supported within the receptacle. The mattress 25 adapts the receptacle 13 for use as a child's crib upon removal of the receptacle from its supported position within the chest 11. The edges of the mattress are spaced inwardly from the edges of the bottom wall 23 to provide a clearance space into which a crib guard rail, to be described hereinafter, may move.

40 35 Telescopically received within the receptacle 13 is a rectangular, open-ended, crib guard rail 26 which is mounted within the receptacle 13 for movement through the open top thereof to an extended position, as illustrated in Figure 2. Suitable interengaging means are provided on the receptacle 13 and the guard rail 26 for detachably securing the latter in its extended position. As clearly shown in Figure 7, the interengaging means embodies a latch piece 30 which is supported within a transversely extending, rec-

tangular opening provided in each of the side walls 19 and 20 of the receptacle 13. Since each of the interengaging means is of like structure, it will suffice to describe only one in detail. The end wall 19 is provided with the rectangular opening 31 and the latch piece 30 is disposed in bridging and closing relation with respect to the opening 31 and has its lower end supported on the bounding walls of the opening for pivotal movement about a horizontal axis by means of the hinge 32. Fixedly secured to an adjacent portion of the guard rail 26 is a keeper 33 which is engageable with the free upper end of the latch piece 30 upon movement of the latter into the position illustrated in Figure 7. A hinge 32 is provided with a spring, not shown, which normally biases the latch piece 30 inwardly for engagement with the keeper 33. It is to be noted that the keeper 33 normally maintains the latch piece 30 in its position of bridging relation with respect to the opening 31 and with the inner wall of the latch piece 30 arranged in coplanar relation with respect to the adjacent inner surface of the side wall 19. However, upon movement of the guard rail 26 to a position wherein the lower end of the keeper 33 is contiguous to the upper end of the latch piece 30, the latter will be swung inwardly, due to the resilient force applied by the spring and maintain the crib guard rail 26 in the position illustrated in Figure 2, until the latch piece 30 is urged back into its normal position by contact with the adjacent outer surface of the keeper 33. The crib guard rail might be removed entirely when the receptacle 13 is accommodating a small, relatively inactive infant. However, older, more active children tend to climb out of a crib, and it is therefore desirable, in such instances, to raise the guard rail. Particularly is this true in those commercial applications of the invention in which the chest, when viewed in top plan, is formed to the general dimensions of a full-size crib and is made with a receptacle 13 of low height.

The drawer 14 includes a front panel 35, the drawer being supported for extensible and retractile movement on a frame 36 which is supported within the chest 11 in spaced, parallel relation contiguous to and below the top wall 17 thereof. The front panel 35 of the drawer 14 is provided with a pair of spaced hand grips 36, 37 to thereby facilitate the grasping of the drawer for movement to its extended position.

The front panel 21 of the receptacle 13 is provided with a plurality of longitudinally spaced, transversely extending notches, generally designated by the reference numeral 37 which subdivides the receptacle front panel 21 into a plurality of sections simulating the drawer front panel 35. Each of the drawer-simulating sections of the receptacle front panel 21 is provided with the hand grips or handles 38 and 39 to facilitate grasping the receptacle 13 to effect the movement of the latter to its extended position.

Dependingly carried by the open-top receptacle 13 are the spaced casters 40 which are adapted to engage the floor surface 24 to thereby movably support the receptacle above the floor surface. In actual use, the combination article of furniture may be kept in the assembled position illustrated in Figure 3 during the daytime, the bedclothing of the child and other wearing apparel being stored within the chest. When the child is to be placed within the crib-providing receptacle 13, the latter can be completely removed from its stored position within the chest

11 and the guard rail 26 extended, as illustrated in Figure 2. The child can be placed within the receptacle 13 wherein it will be maintained in a safe and comfortable position until removed.

5 In Figures 8 and 9, there is shown a modification of the combination article of furniture of the present invention in which the mattress 25, the guard rail 26 and the interengaging means 30 are omitted, to thereby particularly adapt the open-top receptacle 13 for use as a storage device. However, it is to be noted that any suitable spring and/or mattress may be employed with the modified form illustrated in Figures 8 and 9, to particularly adapt the article of furniture for use 10 as a child's crib.

15 Numerous other modifications of the combination article of furniture of the present invention can be made without departing from the spirit of the invention as set forth in the appended claims.

20 What I claim is:

25 1. A combination article of nestable furniture comprising an upstanding hollow chest having an open front, an open-top receptacle including a front panel conformably received within a lower portion of said chest and mounted for horizontal extensible and retractile movement with respect to the open front of the latter, said receptacle in its extensible position being disposed 30 wholly exteriorly of the chest to expose fully its open top, and being nested wholly within the chest when in its retractile position, the front panel of said receptacle forming a closure for the open front of said chest, a mattress resting upon the bottom of said receptacle and supported 35 therein, the periphery of said mattress being spaced inwardly from the side walls of the receptacle to provide a guard rail clearance space, a crib guard rail telescopically received within 40 said receptacle and mounted in the latter for movement to an extended position through the open top thereof, the guard rail in its extended position projecting partially through the open top of the receptacle, said guard rail being disposed 45 wholly within the receptacle with its lower portion in said clearance space when telescoped into the receptacle, and interengaging means on said receptacle and guard rail for detachably securing the latter in its extended position.

50 2. An article of nestable combination furniture comprising a chest having an open front, a receptacle proportioned for horizontal movement into and out of the chest through the open front thereof between an extended position in which it is disposed wholly exteriorly of the chest and a nested position in which it is recessed wholly within the chest, said receptacle having an open top and including a front wall adapted to close 55 said open front of the chest in the nested position of the receptacle, a crib guard rail mounted in the receptacle for vertical movement through the open top thereof between an extended position in which it projects partially out of said open top and a nested position in which it is 60 recessed wholly within the receptacle, and means on the receptacle and crib guard rail, respectively, adapted to interengage releasably in the extended position of the crib guard rail to retain the same in said extended position thereof.

65 3. An article of nestable combination furniture comprising a box-shaped chest having an open bottom and having its front open from the lower end of the chest to a location intermediate the upper and lower ends of the chest, a box-shaped 70 receptacle mounted in the lower end portion of

the chest for horizontal movement into and out of the chest through the open front thereof between an extended position in which it is disposed wholly exteriorly of the chest and a nested position in which it is recessed wholly within the chest, said receptacle having an open top wholly exposed in the extended position thereof and having a closed bottom, the receptacle including a front wall shaped to close said open front of the chest in the nested position of the receptacle, a rectangular crib guard rail formed open at its upper and lower ends and mounted in the receptacle for vertical movement through the open top thereof between an extended position in which it projects partially out of said open top and a nested position in which it is recessed wholly within the receptacle and is supported upon the receptacle bottom, and means on the receptacle and crib guard rail, respectively, adapted to interengage releasably in the extended position of the crib guard rail to retain the same in said extended position thereof.

4. An article of nestable combination furniture comprising a box-shaped chest having an open bottom and having its front open from the lower end of the chest to a location intermediate the upper and lower ends of the chest, a box-shaped receptacle mounted in the lower end portion of the chest for horizontal movement into and out of the chest through the open front thereof between an extended position in which it is disposed wholly exteriorly of the chest and a nested position in which it is recessed wholly within the chest, said receptacle having an open top wholly exposed in the extended position thereof and having a closed bottom, the receptacle including a front wall shaped to close said open

front of the chest in the nested position of the receptacle, the receptacle having an opening formed in one wall thereof, a rectangular crib guard rail formed open at its upper and lower ends and mounted in the receptacle for vertical movement through the open top thereof between an extended position in which it projects partially out of said open top and a nested position in which it is recessed wholly within the receptacle and is supported upon the receptacle bottom, and means on the receptacle and crib guard rail, respectively, adapted to interengage releasably in the extended position of the crib guard rail to retain the same in said extended position thereof, said means including a latch piece hingedly connected to one edge of said opening for swinging movement into and out of the plane of the wall in which the opening is formed, and a keeper secured to the guard rail and disposed for engagement by said latch piece in the extended guard rail position when the latch piece is swung out of the plane of said wall.
